H. A. DOUGLAS

CIRCUIT CONNECTER

Filed Sept. 3, 1925

Inventor:
Harry G. Douglas

By G. L. Gray Atty.

UNITED STATES PATENT OFFICE.

HARRY A. DOUGLAS, OF BRONSON, MICHIGAN.

CIRCUIT CONNECTER.

Application filed September 3, 1925. Serial No. 54,282.

My invention relates to circuit connectors employing shells that carry contacts within their interiors and contact carriers provided with contacts complementary to the aforesaid contacts and adjustably assembled with the shells in order to open and close circuit. Hitherto, these contact carriers, provided for switching purposes, were in the form of plugs located in ends of the shells, these switching plugs being provided with current conducting terminals with which the circuit wires were mechanically and electrically connected. Because of this union between the switching plugs, the current conducting terminals, and the circuit wires, the manipulation of the switching plugs was rendered cumbersome and the mechanical and electrical connections between the circuit wires and the conducting terminals have become impaired.

In carrying out my invention, the circuit connecting plug at one end of the shell is held from rotation with respect to the shell and there is interposed between this plug and the inner contacts within the shell, another set of contacts upon a carrier that is adjustable with respect to the shell to bring the contacts thereon into circuit closing or circuit opening positions. This interposed contact carrier within the shell preferably has pin and slot connection with the skirt of a cap that is located upon the contiguous end of the shell and which skirt preferably surrounds this shell end.

The invention will be more fully explained in connection with the accompanying drawing in which Fig. 1 is a longitudinal view, partially in section and partially in elevation, showing a connector of my invention and a lamp adapted to be included in a circuit thereby; Fig. 2 is a sectional view of a part of the structure shown in Fig. 1 on line 2—2 of Fig. 1; Fig. 3 is a sectional view on line 3—3 of Fig. 1; Fig. 4 is a longitudinal view similar to Fig. 1 but showing the connector in longitudinal section, the lamp being shown in elevation; and Fig. 5 is a sectional view on line 5—5 of Fig. 4.

The shell 1 is preferably metallic and cylindrical or tubular. It has bayonet slots 2 at one end adapted to receive the bayonet pins 3 projecting from the sides of the base 4 of an incandescent lamp 5. At the other end of the shell there is another bayonet slot having an entrance opening 6 and a trans-

verse continuation 7, this transverse continuation of this bayonet slot having seats 8 and 9 for receiving the bayonet pin 10 provided upon the skirt 11 of a cap 12, this cap skirt preferably surrounding the bayonet slot at its end of the shell and being rotatable thereon and movable to a slight extent longitudinally thereof. The bayonet pin 10 projects inwardly from the cap skirt 11 and enters the slot 13 extending lengthwise in an insulating contact carrier 14. This contact carrier supports two spring contact members inclusive, respectively, of metallic spring barrels 15, 16, metallic plunger contacts 17 and 18, and metallic coiled springs 19 and 20 which press upon the plunger contacts and spring barrels in opposite directions. The contact carrier 14 is moved to circuit opening and circuit closing positions preferably by turning the cap 12, from which turning effort is transmitted to the contact carrier 14 through the medium of the bayonet pin 10.

Another contact carrier 21, of insulating material, is fixed within and with respect to the shell 1. This contact carrier supports two spring contact members respectively inclusive of metallic spring barrels 22 and 23, metallic plunger contacts 24 and 25, and metallic coiled springs 26 and 27. In the case of the contact carrier 21, the spring barrels 22 and 23 are fixed in relation thereto, the plunger contacts 24 and 25 alone being urged by the springs 26 and 27 into contacting position. As illustrated in the drawing, the plunger contacts 24 and 25 are thus engaged with the lamp base contacts 28 and 29 that constitute the terminals of the lamp filament 30. The contact carrier 14 is held in a fixed zone of rotation by means of the contact carrier 21 on one side and the ears 31 upon the shell 1 at the other side.

The insulating plug 32 is assembled with the shell by means of tongues 33 carried by and projecting outwardly from the shell and entering slots 34 formed longitudinally in the plug 32. These tongues prevent the plug 32 from turning but permit slight movement of the plug longitudinally of the shell. The plug 32 carries two metallic terminals 35 and 36 which are respectively aligned with the spring barrels 22 and 23 and the plunger contacts in these barrels. These terminal contacts are formed with

bores in which the ends of circuit wires 37 and 38 are received, the binding screws 39 and 40 holding these circuit wires and their terminal contacts together. The cap 12 is provided with an insulating bushing 41 through which the circuit wires extend. The cap is also formed with an annular shoulder 42 against which the springs 19 and 20 press the plug 32 through the intermediation of the plunger contacts 17 and 18, these springs also slightly pressing the base ends of the spring barrels 15, 16 against the base ends of the spring barrels 22 and 23. When the circuit is to be closed, the cap 12 is turned to bring the spring barrels 15 and 16 and the plunger contacts in these spring barrels into alignment respectively with the terminal contacts 35 and 36 and the spring barrels 22 and 23 whereby the lamp terminal 30 is included in circuit as illustrated. In this adjustment, the pin 10 is located in the bayonet seat 9. When the circuit is to be opened, the cap is turned to turn the contact carrier 14 to bring the plunger contacts 17 and 18 into engagement with the insulation of the plug 32 and to bring the base ends of the spring barrels 15 and 16 into engagement with the insulation of the contact carrier 21, the bayonet pin 10 resting in the bayonet seat 8 when this result has been fully brought about. A slight hump 43 intervenes midway between the bayonet seats 8 and 9 to produce a wedge-like cam element that aids in finally moving the bayonet pin 10 to the seat that it is to occupy. This hump 43 causes the cap to move longitudinally on the shell a slight distance when the bayonet pin is riding toward it and the springs 19 and 20 cause a reverse longitudinal movement of the cap when the hump 43 has been passed by the pin 10. During these longitudinal movements of the cap, the plug 32 is caused to move longitudinally therewith, either by the shoulder 42 upon the inner side of the cap when the pin 10 is riding onto the hump 43, or the springs 19 and 20 when the pin 10 is riding from the hump onto one of the bay-

onet seats. The tongues 23 guide the plug 32 in its longitudinal movements but prevent the plug from turning with the result that the wear upon the insulating serving about the conducting wires 37 and 38 is reduced to a minimum and with the further result that strains imposed upon the mechanical and electrical connection between the conducting wires and their terminals is also reduced to a minimum

Changes may be made without departing from the invention.

Having thus described my invention, I claim as new:—

The combination with a tubular shell; of a connecting plug assembled with one end of the shell to have longitudinal movement relatively to the shell and be prevented from having rotary movement respecting the shell; a terminal contact member upon the plug; a contact carrier within the shell and having a contact member supported thereby; a second contact carrier assembled with and within the shell between the aforesaid contact carrier and the plug; a contact member provided upon the second contact carrier and including two contacts respectively engageable with and separable from the contact member upon the plug and the first contact carrier; a slot in the end of the shell where the second contact carrier is disposed, the slot having two seats; a pin entering said slot and a slot formed longitudinally in the second contact carrier; and a cap assembled with the shell and movable longitudinally thereof and adapted to turn with respect thereto, said cap being in actuating relation with the pin, whereby the second carrier is turned with the cap, the seats and the contacts being so related that the contacts upon the second contact carrier serve to close circuit when the pin is in one of its seats and are in open circuit when the pin is in the other one of its seats.

In witness whereof, I hereunto subscribe my name.

HARRY A. DOUGLAS.
